A. Newton Burns, Oklahoma City, Okla.

Application October 15, 1936, Serial No. 105,808

3 Claims. (Cl. 273—95)

The invention relates to a vending machine.

The primary object of the invention is the provision of a machine of this character, wherein through the use of a coin a determined amount of merchandise, such, for example, as peanuts, ball chewing gum or candy pellets will be dispensed from the said machine and the coin deposited will gravitate into a water container and by chance caught into a depository which is swingingly supported within this container and may be manipulated for the delivery of such coin caught onto the bottom of the container, thereby lending interest and attraction to a person when depositing or inserting a coin in the machine.

Another object of the invention is the provision of a machine of this character, wherein merchandise can be vended in a unique manner and through such vending the inserted coin for the control or operation of the machine will be delivered into a water container and therein may be trapped in a depository which is clearly visible thus lending amusement and interest to the operator of the machine, the latter being of novel construction and is controlled by the insertion of a coin of a determined denomination for vending purposes.

A further object of the invention is the provision of a machine of this character, which is comparatively simple in its construction, thoroughly reliable and efficient in operation, neat in appearance, lending attraction in the operation thereof, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a side elevation partly in vertical section of the machine constructed in accordance with the invention.

Figure 2 is a fragmentary vertical sectional view taken at right angles to the section shown in Figure 1.

Figure 3 is a sectional view on the line 3—3 of Figure 1 looking in the direction of the arrows.

Similar reference characters indicate corresponding parts throughout the several views in the drawings.

Referring to the drawings in detail, the machine, which is of the coin controlled type, comprises a circular base 10 formed with a marginal

supporting flange or rim 11 providing a cavity or space 12 in the under side of said base. This cavity 12 is normally closed by a cover plate 13 equipped with a suitable lock 14 of the key type and coating with a keeper 15 formed on the base 10 to be concealed within said cavity or space 12 and in this manner the cover plate 13 is releasably locked and in this condition is in a seat 16 formed in the flange or rim 11 at the inner periphery thereof.

Formed on the base and rising slightly therefrom at diametrically opposite points are perforated lugs or eyes 17 in which are removably fitted tie rods 18 having the threaded lower ends 19 engaged by winged nuts 20, these threaded ends being adapted to project into the cavity 12 so that the nuts 20 will be confined therein and only accessible on the removal of the cover plate 13 for the detachment of the tie rods.

Adapted to be counterseated in the upper face of the base 10 is a water container or jar 21 of glass having an open mouth 22 on which is fitted a removable cap 23, it having a gasket 24 for sealing the cap when removably placed upon the mouth 22 of said container. This cap interfits 25 a head 25 having the perforated ears 26 for accommodating the tie rods 18 so that the latter will separably fasten the head 25 in place and interfit with the cap 23 when upon the container 21.

The head is constructed to accommodate therein suitable coin controlled mechanism (not shown) for the dispensing of merchandise from a globe-like carrier or receptacle 27 of glass, the merchandise being in the nature of shelled peanuts 28 as contained within this receptacle. However, it is to be understood that such receptacle may contain ball chewing gum, candy pellets or other like merchandise. This head is formed with a coin insert or receiving chute 29 adapted for the reception of a coin of a determined denomination or size for actuating the coin controlled mechanism whereby a determined quantity of merchandise can be delivered without the machine through a delivery trough 30 on actuating a trigger 31 which is released by the coin mechanism and acts as an operator for a shutter, gate or the like (not shown) for the dispensing of the merchandise from the receptacle 27 through the trough 30 when a coin has been deposited in the machine.

The receptacle 27 has a removable cover 32 which is held secure and can only be removed when the head 25 is detached from the container 33.

21 and when such cap is removed the receptacle
27 can be filled with merchandise.

The head 25 centrally thereof is constructed on
the insertion of a coin through the chute 29 to de-
5 liver this coin into a lead 33 opening into the
container 21 and such lead extends through a
suitable clearance 34 in the cap 23 when upon the
mouth 22 of the container so that the coin will be
10 freed into a quantity of water or other liquid con-
tent 35 within the said container 21 to gravitate
in the direction of the bottom of the latter.

Removably fitted within the container 21 onto
the bottom thereof is a spider 36 forming a cradle
or holder 37 for swingingly supporting a deposi-
15 tory or trap in the form of a small jug 38, it being
removably fitted in a split ring clamp 39 having
trunnions 40 journaled in the cradle 37 for the
vertical tilting or swinging of said jug 38. One of
20 the trunnions 40 is formed with a crank 41 pivoted
at 42 to an actuating or throw lever 43 which ex-
tends upwardly through suitable clearances in
the cap 23 and head 25 to be projected exteriorly
25 of this head for manual manipulation. This lever
43 when manually actuated will cause the tilting
25 of the jug 38 and the aim of the operator of the
machine is to have the coin freed within the liquid
within the container 21 fall within the jug 38
and through manual manipulation of the lever
30 43 drops from such jug onto the bottom of the
container 21 interiorly thereof. This procedure
lends amusement and interest to the operator of
the machine.

The coins deposited within the container 21 are
removed therefrom when the said container is
35 taken from the machine, this requiring the re-
moval of the head 25 and the detachment of the
tie rods 18 from the base 10 of said machine.

What is claimed is:

1. A machine for use with a coin controlled
vending mechanism comprising a base, a liquid
filled container fitting said base, a head covering
the container and releasably tied with the base
5 and disposed between the vending mechanism and
the container, said head having an opening for
the passage of a coin therethrough, and a coin re-
ceiving tiltable trap confined within the container
10 beneath the opening in said head for the deposit
of a coin admitted to said container from the coin
controlled mechanism.

2. A machine for use with a coin controlled
vending mechanism comprising a base, a liquid
filled container fitting said base, a head covering
15 the container and releasably tied with the base,
said head having an opening for the passage of
a coin therethrough, a coin receiving tiltable
trap confined within the container beneath the
opening in said head for the deposit of a coin ad-
20 mitted to said container from the coin controlled
mechanism, and a manually operated lever ac-
cessible without the head for tilting said trap.

3. A machine for use with a coin controlled
vending mechanism comprising a base, a liquid
filled container fitting said base, a head covering
25 the container and releasably tied with the base,
said head having an opening for the passage of
a coin therethrough, a coin receiving tiltable trap
confined within the container beneath the open-
30 ing in said head for the deposit of a coin ad-
mitted to said container from the coin controlled
mechanism, a manually operated lever accessible
without the head for tilting said trap, and a
spider forming a cradle within the container for
35 swingingly supporting the trap.
